UNITED STATES PATENT OFFICE

ISADORE ROSENBLUM, OF BALTIMORE, MARYLAND, ASSIGNOR TO MARLBORO SHIRT COMPANY, INC., A CORPORATION OF MARYLAND

CONVERTIBLE SHIRT

Application filed October 30, 1930. Serial No. 492,278.

This invention relates to a convertible shirt and has for its primary object to provide, in a manner as hereinafter set forth, a shirt which may be worn as a collar attached 5 soft shirt in the usual manner, or as a sport shirt, as desired.

A further object of the invention is to provide a convertible shirt of the character aforesaid which includes an attached collar 10 adapted to receive a necktie in the usual manner, and which is adapted further to have a portion thereof turned down to form a pair of lapels in the event that it is desired to dispense with the necktie.

15 A further object of the invention is to provide a convertible shirt having an attached collar of the character aforesaid, in which the neckband portion of the collar is entirely free from buttons or other securing means in order that the collar may present an attractive appearance when a portion thereof is turned down to provide a sport shirt.

20 A further object of the invention is to provide a convertible shirt having an attached collar of the character aforesaid which will hold its shape when worn either as a conventional attached collar or as the collar of a sport shirt, the collar being constructed in a manner to obscure from view all stitches 25 therein when the same is worn as a conventional attached collar.

With the foregoing and other objects in view, the invention consists of the novel construction, combination and arrangement of 30 parts as hereinafter more particularly described, and as illustrated in the accompanying drawings wherein is shown an embodiment of the invention, but it is to be understood that the description and drawings are 35 to be taken as illustrative and that the invention is intended to be limited only by the scope of the claims hereunto appended.

In the accompanying drawings in which like numerals are employed to designate like 40 parts throughout the several views:

Figure 1 is a fragmentary elevation of a shirt in accordance with this invention showing the appearance of the collar when the shirt is worn as a sport shirt.

50 Figure 2 is a similar view showing the ap-

pearance of the collar when the shirt is worn as a conventional collar attached shirt.

Figure 3 is a fragmentary elevation showing the inner face of the collar with the latter opened out to show the contour thereof.

55 Figure 4 is a similar view showing the outer face of the collar.

Figure 5 is an enlarged section taken on the line 5—5 of Figure 1.

Referring to the drawings in detail, the 60 numeral 1 indicates the open front body portion of a shirt in accordance with this invention, the body portion being of the usual construction, having a neck opening, the usual reinforcing member 2 on the inside and at 65 the back thereof, the usual overlapping portions at the front thereof formed by the reinforcing strips 10, 11 and further having secured thereto my improved collar indicated generally at 3. The collar 3 includes an 70 outer part 4, an inner part 5, and an intermediate part 6, the latter conforming in contour to the inner part 5. The inner part 5 includes a skirt portion 7 and a neckband portion 8, the latter being provided at its ends 75 with angular projections 9 which extend beneath and are secured to the usual reinforcing strip 10 at the front of the shirt where the latter is buttoned. The parts of the collar are bent upon themselves to provide a 80 pair of folds.

The outer part 4 includes a skirt portion 11 and a neckband portion 12, the end portions of the latter projecting laterally beyond the skirt portion 11 and extending over and being secured to the strip 10. The projecting end portions of the neckband portion 12 are indicated by the numeral 13.

The inner part 5, outer part 4, and intermediate part 6 are secured to each other and to the body 1 by means of a row of stitches 14, said parts respectively being provided at their inner edges with inturned hems 15, 16 and 17 respectively, through which said row of stitches 14 extends. In other words, the 90 row of stitches 14 extends through the parts 5, 4 and 6, the hems 15, 16 and 17, the body 1 and the reinforcing member 2.

The ends of the neckband portions project 95 beyond the ends of the skirt portions of the 100

parts 4, 5 and register with each other. The part 4 has the neckband portion thereof secured to the outer face of body portion 1 at the edge of the neck opening and the extended ends of said neckband portion are disposed transversely of and secured to the outer faces of the strips 10, 11. The neckband portion of the part 5 is secured to the inner face of body portion 1 at the edge of the neck opening and the projections of said part 5 are secured to the inner face of body portion 1 adjacent the neck opening and to the inner faces of strips 10, 11 lengthwise of the latter.

The ends of the parts 4, 5 have inner edge portions, intermediate edge portions extending inwardly from the inner edge portions and outer edge portions disposed at an outward inclination with respect to said intermediate and inner edge portions. The inner end of part 5 has an intermediate edge portion of arcuate form and a pair of outer edge portions. The inner edge portions at the ends of part 5 are of greater length than the inner edge portions at the ends of part 4. The arcuate edge portion of part 5 provides for such part to gradually decrease in width from a point removed from each end to its center thereby providing the projections 9.

The skirt portions of the parts 4, 5 and 6 are secured together at their outer edges by means of a row of stitches 18, said parts being formed at their outer edges with turned hems 19, 20 and 21 respectively, through which the row of stitches 18 extends. The row of stitches 18 further extends through the intermediate part 6 proper, but does not extend through the outer and inner parts 4 and 5 proper, in order that the row of stitches 18 will be invisible when the collar 3 is fully assembled with respect to the body portion 1.

The stitching which holds the uppermost button 22 of the shirt in position extends through one of the angular projections 9 adjacent the free end of such projection, and the uppermost buttonhole 23 of the shirt extends through the other projection 9 adjacent the free end thereof.

When the collar is worn in a manner to provide a conventional, collar attached shirt having the usual spaced collar points 27, the projecting portions 9 and 13 at one end of the collar extend in overlapping relation to the similar projections at the other end of the collar and are adapted to be held in overlapping relation by means of a necktie, not shown, worn in the usual manner. When the collar is so worn, the fold 24 between the skirt portions and neckband portions of the collar is substantially on a line with the upper edges 25 of the projections 13. When the collar is worn in a manner to provide a sport shirt, the projections 13 and portions of the projections 9 are turned back to provide a pair of lapels 26, and to spread the spaced collar points 27 to the position shown in Fig-

ure 1. When the collar is worn in this manner, the fold 24 is disposed inwardly of the upper edges 25 of the projections 13 and extends at an angle to said upper edges.

It is to be noticed that the intermediate part 6 of the collar provides the latter with a thickened body to insure the proper laying thereof when adjusted to provide either a conventional collar or a sport collar. It is to be noticed further that the angular projections of the inner part 5, as well as the corresponding projections on the intermediate part 6 substantially increase the thickness of the shirt at the location of the uppermost button 22 whereby the lapels 26 are provided with the necessary thickness to insure the proper laying thereof.

It is thought that the many advantages of a shirt in accordance with this invention will be readily apparent, and although the preferred embodiment of the invention is as illustrated and described, it is to be understood that changes in the details of construction may be resorted to, so long as such changes fall within the scope of the invention as defined in the appended claims.

What I claim is:—

1. In a convertible shirt of that type including a split front body having a neck opening and a pair of overlapping front portions, one provided with a buttonhole and the other with a button on its outer face, a convertible two-fold collar including an inner and an outer part bent to provide a pair of folds, said inner part formed of a skirt portion, a neckband portion having its ends extended from the skirt portion and a pair of oppositely inclined inwardly extending projections at the ends of the neckband portion positioned against the inner face of said overlapping front portions, said outer part formed of a skirt portion and a neckband portion having its ends projecting from such skirt portion, said skirt portions registering with each other, the ends of said neckband portions registering with each other, means for securing the neckband portion of said inner part to the inner face of said body at the edge of said neck opening, means for securing the projections to the inner face of said body adjacent said neck opening, means projecting against the inner faces of said overlapping front portions lengthwise of the latter, means for securing the neckband portion of said outer part to the outer face of said body at the edge of said neck opening, means for securing the extended ends of such neckband transversely of the outer faces of said overlapping front portions, and one of said projections having in proximity to its inner end a buttonhole registering with the buttonhole in an overlapping portion.

2. In a convertible shirt, a convertible two-fold collar including an inner part and an outer part bent to provide a pair of folds,

each of said parts having each end edge thereof formed with an inner portion and an outer portion inclined with respect to said inner portion, the inner portions of the end edges of the inner part being of greater length than the inner portions of the end edges of the outer part, and said inner part having its inner side edge formed with an intermediate portion of arcuate contour to provide said inner part with inwardly extending projections at said inner edge.

In testimony whereof, I affix my signature hereto.

ISADORE ROSENBOOM.
